C. W. CUNNINGHAM.
MEAT SKINNING MACHINE.
APPLICATION FILED MAY 26, 1914.

1,111,952.

Patented Sept. 29, 1914.

UNITED STATES PATENT OFFICE.

CLINTON W. CUNNINGHAM, OF BALTIMORE, MARYLAND, ASSIGNOR TO KINGAN & COMPANY, LIMITED, OF INDIANAPOLIS, INDIANA, A CORPORATION OF GREAT BRITAIN.

MEAT-SKINNING MACHINE.

1,111,952.

Specification of Letters Patent. Patented Sept. 29, 1914.

Application filed May 26, 1914. Serial No. 841,115.

To all whom it may concern:

Be it known that I, CLINTON W. CUNNINGHAM, of Baltimore, State of Maryland, have invented certain new and useful Improvements in Meat-Skinning Machines; and I do hereby declare the following to be a full, clear, and exact description of the invention, such as will enable others skilled in the art to which it appertains to 10 make and use the same.

This invention relates to improvements in meat skinning machines and more particularly to machines for removing the skin from bacon,—the object of the invention being to 15 provide simple and efficient means which shall be easily operable to accurately, neatly and quickly remove the skin from bacon without appreciable waste, and to provide simple means for effecting necessary or de- 20 sirable adjustments.

With this and other objects in view, the invention consists in certain novel features of construction and combinations of parts as hereinafter set forth and pointed out in 25 the claims.

In the accompanying drawings; Figure 1 is a longitudinal sectional view of a machine embodying my improvements, and Fig. 2 is a transverse sectional view.

1 represents a table supported by suitable framework 2 and having upon its upper face, two parallel strips 3, 3 spaced apart to form a groove or guideway 4 between them, said strips being provided on their 35 upper faces with wear plates 5 for a purpose hereinafter explained. At one end of the guide strips 3, a frame 6 is rigidly secured and includes in its structure, standards 7 at respective ends. The upper ends of the 40 standards may be made with lateral projections 8 which afford extended bearings for a fixed blade 9 extending from one standard to the other and rigidly secured in place by means of screws 10. Near the 45 base of the fixed frame 6, a hinged frame 11 is pivotally supported as at 12, and projects horizontally through the fixed frame 6 between the standards thereof. A roller frame 13 is pivotally supported by the 50 hinged frame 11 and is formed with bearings 14 for the journals of a roller 15 operatively disposed under the cutting edge of the blade 9,—adjustment of said roller in an approximately horizontal direction relatively to the blade being effected by means 55 of thumb screws 16 passing through portions of the hinged roller frame and engaging the standards of the fixed frame 6. The hinged roller frame is also provided with handles 17 to permit the roller to be swung 60 back and thus facilitate the placing of a piece of bacon to be skinned. The horizontal hinged frame 11 has swiveled thereto near its free end, the upper end of a thumb screw 18, the latter being threaded through 65 a suitable hole in the base portion of the fixed frame 6 and having its head disposed in an opening 19 in the table 1. By means of the thumb screw 18, the horizontal frame 11 may be moved on its pivotal support and 70 in this manner, the roller 15 may be adjusted vertically with respect to the blade to regulate the depth of cut according to the thickness of the skin on the bacon to be skinned. 75

It is customary to sever a small portion of the skin at one end of the piece of bacon before subjecting the latter to the machine and then place the piece of bacon in the position substantially as shown in Fig. 1, 80 with the body of the meat disposed over the blade and the severed end of the skin projecting under said blade. The projecting end of the skin will then be caused to be grasped between the jaws 20 of a clamp 21. 85 This clamp comprises two levers 22—23 pivotally connected together, and a spring 24 tends to close the jaws 20. These jaws are sufficiently elongated to grasp the skin of a piece of bacon substantially from one 90 edge to the other thereof and when the clamp is moved to effect the skinning operation or to return to position near the blade, said jaws may ride upon the wear plates 5 on the strip 3, while the free end of the 95 lever 22 may move in the groove or guideway formed between said strips.

A drum 25 is mounted in suitable bearings on the framework below the plane of the table 1 and is provided with a suitable 100 manually operable crank 26. A rope 27, or equivalent flexible device is wound upon the drum 25 and after passing through a hole 28 in the table, is secured to the free end of the lever 22 of the clamp. Another 105 rope 29 or equivalent flexible device, is wound in the reverse direction upon the drum 25 and extends therefrom to the far end of the table where it passes over a pulley 30 mounted in a suitable opening in 110

the table. From the pulley 30, the rope 29 extends forwardly and after passing over a pulley 31 mounted at the free end of lever 23 of the clamp 21, is secured to the free end 5 of the clamp lever 22.

It will be observed that when the bacon is positioned and the skin thereof is grasped by the jaws of the clamp as shown in Fig. 1, rotation of the drum 25 in one direction 10 will cause the jaws of the clamp to tighten their grip upon the bacon skin and the clamp will be moved bodily, thus pulling the bacon past the blade and effecting the clean severance of the skin. By rotating 15 the drum in the reverse direction, the clamp will be returned to position to be engaged with the skin of another piece of bacon.

Various changes might be made in the 20 details of construction of my invention without departing from the spirit thereof or limiting its scope and hence I do not wish to restrict myself to the precise details herein set forth.

Having fully described my invention what 25 I claim as new and desire to secure by Letters-Patent, is:—

1. In a machine of the character described, the combination with a table, of a fixed frame thereon, a blade on said fixed frame, a swinging roller frame, a roller mounted in said roller frame, means for adjusting roller frame, and a clamp for pulling material past the blade.

2. In a machine of the character described, the combination with a table, a blade secured to said fixed frame, a swinging roller frame, a roller mounted in said roller frame, means for adjusting the roller

frame, a clamp to engage material to be pulled past the blade, and operating means 40 for moving said clamp over the table.

3. In a machine of the character described, the combination with a table, of a fixed frame thereon, a blade secured upon said fixed frame, a horizontal hinged frame, 45 a roller frame hinged to the horizontal hinged frame, a roller mounted in the roller frame below the blade, and means for adjusting the horizontal hinged frame to adjust the roller relatively to the blade.

4. In a machine of the character described, the combination with a table, of a fixed frame thereon, a blade on said fixed frame, a horizontal hinged frame projecting through the fixed frame, a roller frame 55 hinged to the horizontal hinged frame, a roller mounted in said roller frame below the blade, and a thumb screw passing through the base of the fixed frame and swiveled to the horizontal hinged frame.

5. In a machine of the character described, the combination with a table, of a fixed frame thereon, a blade on said fixed frame, a swinging roller frame, a roller mounted in said roller frame, means for adjusting said roller frame horizontally and means for adjusting said roller frame vertically.

In testimony whereof, I have signed this specification in the presence of two sub- 70 scribing witnesses.

CLINTON W. CUNNINGHAM.

Witnesses:

DAVID L. EMERICK,
J. LOGAN DUNCAN.
